Attorney.

UNITED STATES PATENT OFFICE.

WALTER B. PEDELTY, OF MASON CITY, IOWA, ASSIGNOR TO THE AULTMAN AND TAYLOR MACHINERY COMPANY, OF MANSFIELD, OHIO.

VEHICLE-AXLE.

1,258,445.

Specification of Letters Patent.

Patented Mar. 5, 1918.

Application filed July 9, 1917. Serial No. 179,897.

To all whom it may concern:

Be it known that I, WALTER B. PEDELTY, a citizen of the United States, residing at Mason City, in the county of Cerro Gordo 5 and State of Iowa, have invented certain new and useful Improvements in Vehicle-Axes; and I do hereby declare the following to be a full, clear, and exact description of the invention, such as will enable others 10 skilled in the art to which it appertains to make and use the same.

This invention relates to the front or steering axles of tractors or motor cars; and it consists in the novel construction and 15 combination of the parts hereinafter fully described and claimed.

In the drawings, Figure 1 is a front view of a steering axle constructed according to this invention. Fig. 2 is a plan view 20 of the axle. Fig. 3 is an end view of the axle. Fig. 4 is a cross-section through the axle, taken on the line $a-a$ in Fig. 2.

The main frame 2 of the vehicle or tractor is of any approved construction. Two 25 similar angle-shaped brackets 3 are provided, and are secured parallel to each other and crosswise of the front end portion of the frame 2. The upper ends 4 of these brackets are turned so that they lie flat 30 against the sides of the frame, and they are secured to it by rivets 5. The apices of the brackets project downwardly of the frame, and 6 is a block provided with laterally projecting trunnions 7 which are 35 pivoted in the lower end portions of the brackets 3 on the longitudinal axis of the tractor.

An axle frame is provided, and it comprises parallel upper and lower bars 8 and 40 9, suitably connected together by two vertical distance pieces 10 arranged at a little distance apart and one on each side of the center of the block 6, and a brace or braces 12 secured diagonally between the 45 middle and the end portions of the bars 8 and 9.

A vertical pin 14 is secured to the bars 8 and 9 in the space between the two distance pieces 10, and the block 6 is slidable vertically on the pin 14. A helical spring 15 is arranged to encircle the pin 14 in the space between the two distance pieces, and between the block 6 and the lower bar 9 of the axle frame. The weight of the front 55 end portion of the main frame 2, and the

parts carried by it, rests on this spring 15 which prevents the jolts due to the roughness of the road from being transmitted to an injurious extent to the main frame.

Bearing blocks 16 are pivoted by vertical pins 17 between the upper and lower bars 8 and 9, at the end portions of the axle frame. The bearings 18 of these blocks are arranged to one side of, and preferably in front of, the pins 17. Axle spindles 20 are 60 provided and are carried by the bearings 18, and front road wheels 21 of any approved construction are journaled on the spindles 20. The bearing blocks have forwardly projecting arms 22, and 24 is a coupling-rod pivoted between the free end portions of the arms 22. One of the axle spindles has a cranked extension 25, and 26 is a portion of the steering-rod which is pivoted to the extension 25. The rod 26 is operated 70 by any approved means, and it operates the two steering road wheels simultaneously. Suitable braces 27 are also provided, and are connected to a crossbar 28 on the main frame and to the axle frame, so as to permit 75 the main frame to move vertically under the control of the spring 15, and so as to hold the axle frame crosswise of the main frame.

These braces 27 are arranged and secured 80 in any approved way, and they are preferably diverging spring braces, and are inclined downwardly and forwardly, and have their front ends secured to the lower bar 9 of the axle frame.

A steering axle constructed in this manner is inexpensive to manufacture, and it is relatively light and strong, and is not liable to get out of order.

What I claim is:

1. The combination, with a main frame, and a pair of brackets secured crosswise thereof and projecting downwardly; of a block provided with trunnions which are pivoted in the said brackets, an axle frame comprising upper and lower bars suitably braced together, means for holding the axle frame crosswise of the main frame, a pin secured to the middle parts of the said bars and slidable vertically in a hole in the said block, a helical spring arranged between the said block and the lower bar of the axle frame, and axle spindles for the road wheels connected to the end portions of the axle frame, 100 105 110

2. The combination, with a main frame, and a pair of brackets secured crosswise thereof and projecting downwardly; of a block provided with trunnions which are pivoted in the said brackets, an axle frame comprising upper and lower bars suitably braced together, means for holding the axle frame crosswise of the main frame, a pin secured to the middle parts of the said bars and slidable vertically in a hole in the said block, a helical spring arranged between the
- 5
- 10

said block and the lower bar of the axle frame, bearing blocks pivoted by vertical pins between the end portions of the bars of the axle frame and provided with bearings arranged to one side of their pivot pins, and axle spindles for the road wheels projecting from the said bearings.

In testimony whereof I have affixed my signature.

WALTER B. PEDELTY.
